METHOD FOR MAKING ARTISTS' CANVAS PANELS

Stan M. Silver, New York, N. Y., assignor to Master Technique Board Co., New York, N. Y.

Original application November 10, 1947, Serial No. 785,004, now Patent No. 2,470,416, dated May 17, 1949. Divided and this application May 14, 1949, Serial No. 93,283

8 Claims. (Cl. 154—116)

1

The present invention relates to methods for producing canvas panels for artists' use of the type described and claimed in my co-pending application Serial No. 785,004, filed November 10, 1947 which has matured into Patent No. 2,470,416 on May 17, 1949, and the instant application is a division of the said co-pending application.

The artists' canvas panel of my invention has been made with the idea of affording artists a canvas panel embodying all the advantages of both two previous known devices, to wit, what is known as a canvas stretcher and what is known as a canvas panel or canvas-board panel.

Canvas stretchers, several kinds of which are known, afford the artist a perfect working surface, due to the slight give of the stretched canvas under pressure of the brush. Such advantage is balanced, however, by the fact that many types of canvas stretchers are apt to warp and lose their shape to become unfit for use. Another disadvantage may be summed up by pointing out that the relatively high cost of a well made and dependable stretcher, as compared to a canvas board panel is as great as four to one. A lesser disadvantage of a canvas stretcher is its weight and bulk. Its bulk does not permit it to be carried, assembled, in a paint box; the artist having to stretch the canvas in the field, with considerable loss of painting time and effort. Also, after the canvas is painted, it must be carried carefully, to avoid smudging and cannot be inserted into the grooves generally provided in paint boxes for canvas board panels.

Further disadvantages of canvas stretchers are that their bulk makes it difficult to carry more than one at a time and that they present difficulties in stretching the canvas thereon uniformly or to the proper tension and that, occasionally, excess pressure may result in the breaking or cracking of the stretcher or the tearing of the canvas.

The canvas board panel came into existence to afford the amateur artist a ready-to-paint canvas surface, at low cost to bring it within the purchasing range of the majority of the painting public, and in compact form.

The principal objections to canvas board panels are that they are easily subject to severe warping; they present a rigid painting surface which responds sluggishly to the brush; and they may be readily dog-eared at the corners and otherwise damaged during handling or if dropped.

The canvas panel of the present invention is characterized by an appearance somewhat similar to the conventional canvas board panel and, while possibly of slightly higher cost than the

2

canvas board panel, has the advantageous features of being compact and light in weight and capable of being conveniently carried in the slots of the paint box, and of presenting a highly taut ready-to-paint canvas surface which is even superior in sensitivity of response to the paint brush than that of the conventionally stretched canvas, and of being immune to warping and to ready damage or dog-earing.

10 A feature of the invention is the methods by which the panels of the invention may be produced which are simple and easy to practice; which may be practiced with great economies of time, labor and materials; which do not require 15 any specially built or complicated machinery; which are capable of mass production; and which are highly effective for the purpose of producing the canvas panels of the characteristics pointed out above.

20 The methods of the present invention will become readily comprehensible to any one skilled in the art from the description following, particularly when considered in connection with the accompanying drawings illustrating one embodiment of an artist's canvas panel of the present invention, in which:

Fig. 1 is a plan view of the painting side of a canvas panel of the invention, partly broken away to show details of assembly;

30 Fig. 2 is a plan view of the back or reverse side of the canvas panel, likewise partly broken and in section to show details of assembly, with the outline of the original shape of the canvas blank shown in broken lines; and

35 Fig. 3 is a fragmentary sectional view taken on line 3—3 of Fig. 2.

Referring more specifically to the accompanying drawings, the canvas panel of the present invention is formed, essentially, of a continuous rigid frame, 10, and of a sheet or blank of canvas, 11, whose edges encompass the frame 10.

40 The frame 10 may be formed of any suitable material of sufficient rigidity to withstand the tension of a tautly stretched canvas thereon, such as of heavy gauge rigid steel or other metallic wire, or of synthetic plastic material of round or other cross section, and may be of rectangular or any other conventional shape, with the ends of the wire or the like forming it preferably secured 45 to one another as by welding, soldering, or the like.

45 The blank 11 may be formed of any canvas or the like having a surface suitable for receiving oil paint or the like on it, and may be made of a 50 length and width greater than the length and width of the frame 10, sufficient to provide a mar-

ginal portion 12, on all sides of the frame 10, adequate to cover the frame and overlap it. Preferably, the length of the blank 11 may be cut from the length of the fabric from which it is taken.

After the canvas blank 11 is formed, a thin layer or coat 13, of a flexible glue, preferably a flexible animal glue and preferably in hot state, is applied to the entire reverse or non painted side of the canvas 11, and the canvas blank is then allowed to stand until the coating of glue 13 becomes tacky. The frame 10 is then positioned centrally of the blank 11, on its coated side, with the length of the frame along the length of the blank, and the marginal portions 12 of the blank 10 then folded over the sides of the frame and against the coated side of the blank 11, to completely enclose the frame sides. The marginal edge 12 is then smoothed out and pushed or tucked flush against the frame sides, as illustrated in Fig. 3, by a suitable sharp tool.

It may here be stated that the marginal portion 12 may, if desired, be skived before the application of the glue coating 13, for smoother finish, and that, for the same purpose, the corners of the canvas 11 may be slit or formed with a dart, in a manner readily understood and not thought necessary to be specifically illustrated.

While the frame 10 may be placed directly upon the coated side of the canvas 11, as described above, it has been found preferable to prepare a thin paper or cardboard sheet or tag 15, of the same size and outline as the frame 10, and set that sheet first on the coated center of the canvas 11, wipe it to eliminate any possible air bubbles, and then place the frame 10 on the tag 15, with its edges resting on the edges of the tag 15, and then arrange the margin 12 over the frame sides, as described above, with the overlap glued to the back of the tag 15.

If desired, a glued sheet of paper, 16, may be applied to the back of the panel, against the back of the tag 15 and over the marginal portions 12 of the canvas 11, between the sides of the frame 10, to provide a smooth, finished appearance for the back of the panel and to give more body to the painting area of the canvas panel.

Panels, when completed as above, may then be stacked, preferably between heavy sheets of cardboard or the like, for several days to allow them to be dried and shrunk; the boards between the panels preventing any possible disfiguration and twisting or buckling during the drying and shrinking process. The possibility of distortion and buckling is also reduced by the practice described of cutting the canvas blank 11 with its length along the length of the material from which it is taken and of arranging the length of the frame along the length of the blank, whereby the direction of greatest shrinkage, which is along the length, is resisted by the strongest or most rigid side of the frame, which is its width or the shortest frame sides.

This completes the description of the methods for making the artists' canvas panels of the present invention. It will be readily apparent that such methods are simple to practice; that they require no special or costly machinery, tools or equipment; that they may be practiced on a production line basis for economical mass production; and that they are highly effective and efficient for their purposes.

It will also be apparent that numerous modifications and variations in the methods of the present invention may be made by any one skilled

in the art, in accordance with the principles of the invention hereinabove set forth and without the use of any inventive ingenuity. I desire, therefore, to be protected for any and all such modifications and variations that may be made within the spirit of the present invention and the scope of the claims hereto appended.

What I claim is:

1. The method of making a canvas panel of the type comprising a sheet of canvas having embedded therein a skeletal polygonal frame which involves applying said frame flatwise against an adhesively coated side of a flatly disposed sheet of canvas, said sheet being cut so as to have a marginal length thereof projected beyond each side of the latter when the frame is substantially centered against said sheet, the frame being thus centered in applying it to the sheet as aforesaid; laying the marginal lengths as flaps over the sides of the frame pressing the flaps down against the back of said sheet; and then treating said sheet to shrink the same.

2. The method of forming an artist's canvas panel comprising the steps of forming a continuous rigid frame, preparing a canvas sheet of greater width and length than said frame, applying a coat of a flexible adhesive over the entire area of one side of said canvas sheet, arranging the said frame substantially centrally on the coated side of said canvas sheet, folding the projecting marginal portions of said canvas sheet over the sides of said frame and against the coated side of the said canvas sheet and then drying and shrinking the said canvas sheet.

3. The method of forming an artist's canvas panel comprising the steps of forming a continuous rigid frame, preparing a canvas sheet of greater width and length than said frame, applying a coat of a hot adhesive which is flexible when dried over the entire area of one side of said canvas sheet, arranging the said frame substantially centrally on the coated side of said canvas sheet, folding the projecting marginal edges of said canvas sheet over and against the sides of the said frame and against the coated side of the said canvas sheet and then drying and shrinking the said canvas sheet.

4. The method of forming an artist's canvas panel, comprising the steps of forming a continuous rigid frame, preparing a canvas sheet of greater width and length than said frame, applying a coat of a hot, flexible animal adhesive over the entire area of one side of said canvas sheet, arranging the said frame substantially centrally on the coated side of said canvas sheet, folding the projecting marginal edges of said canvas sheet over and against the sides of the said frame and against the coated side of the said canvas sheet and then drying and shrinking the said canvas sheet.

5. The method of forming an artist's canvas panel, comprising the steps of forming a metal wire frame of continuous character, preparing a canvas sheet of greater length and width than said frame, applying a coat of a hot, flexible adhesive over the entire area of one side of said sheet, arranging the said frame substantially centrally on the said coated side of said canvas sheet, folding the projecting marginal edges of said sheet and adhesively securing them over and against the sides of the said frame and the coated side of said sheet and then drying and shrinking the said canvas sheet under flatly applied pressure.

6. The method of claim 5, wherein the ends

of the wire forming the frame are connected to one another.

7. The method of claim 5, wherein the adhesive utilized is an animal glue.

8. The method of forming an artist's canvas panel, comprising the steps of forming a continuous metal wire frame, preparing a canvas sheet of greater length and width than said frame, preparing a thin cardboard tag sheet of the same shape and size as the said frame, applying a hot, flexible adhesive coating to the entire area of one side of said sheet, adhesively securing the said tag centrally on the coated side of said sheet, arranging the said frame on the said tag sheet, folding the projecting portions of said sheet and securing them over and against the sides of the said frame and the said tag and then drying and shrinking the said sheet under flatly applied pressure.
